UNITED STATES PATENT OFFICE.

ALBERT J. HORTON, OF WHITE PLAINS, NEW YORK, ASSIGNOR TO THE CUTLER-HAMMER MFG. CO., OF MILWAUKEE, WISCONSIN, A CORPORATION OF WISCONSIN.

RHEOSTAT.

1,130,976.

Specification of Letters Patent.

Patented Mar. 9, 1915.

Application filed September 9, 1912. Serial No. 719,341.

To all whom it may concern:

Be it known that I, ALBERT J. HORTON, a citizen of the United States, residing at White Plains, in the county of Westchester 5 and State of New York, have invented new and useful Improvements in Rheostats, of which the following is a full, clear, concise, and exact description, reference being had to the accompanying drawing, forming a 10 part of this specification.

My invention relates to improvements in rheostats.

It is one of the objects of my invention to provide a simple, compact, and efficient rheostat especially adapted for electric fans, but which may also be used for various other purposes.

Various other objects and advantages of my invention will hereinafter appear.

For the purpose of disclosing my invention I shall describe the embodiment thereof illustrated in the accompanying drawing, it being understood that my invention is susceptible of modification.

In the accompanying drawings, Figure 1 is a top plan view of the rheostat; Fig. 2 is a bottom plan view thereof; Fig. 3 is a section taken on the line 3-3 of Fig. 1; Fig. 4 is a section taken on line 4-4 of Fig. 1; and 30 Fig. 5 is a section taken on line 5-5 of Fig. 1.

The several parts of the rheostat are mounted upon an insulating block or base 10. This base carries the resistance, the terminals, and the resistance regulating contacts. In practice, it may be of any desired shape, size and material. I prefer, however, to form the base of porcelain. As illustrated, the base is substantially circular and 40 provided with a reduced portion forming a continuous recess or groove 11 across and around the same for receiving the resistance 12. The resistance preferably comprises suitable wire which is wound around the base between and parallel to the walls of the recess 11 and the recess is preferably made of such a width as to accommodate the desired amount of resistance wire in a single layer. This is advantageous, for 50 where the wire is wound in several layers the adjacent layers must be insulated from one another. Further, the arrangement of the resistance in the manner illustrated is advantageous in that it enables the use of a thin base and distributes the resistance over

a large area which facilitates and expedites the dissipation of the heat from the resistance. Taps or terminal leads 13 are taken off of the resistance 12 at suitable points. The leads 13 may be readily connected to 60 the resistance by providing small holes 14 in the base 10 and passing the ends of the leads through these holes one or more times to bind the same against the turns of the resistance wire. The ends of the leads 13 65 may be soldered if desired.

The leads 13 are connected to contacts 15. These contacts, as illustrated, each comprise a screw 15 extending through an opening in the base 10 and secured in place by a nut 15^b. 70 The nuts 15^b also serve to bind the ends of the leads to the contacts. As illustrated, there are three leads and four contacts, one of the contacts being dead. Of course, in practice, there can be as many taps and corresponding contacts as desired.

Coöoperating with the contacts 15 is a lever 16. This lever is pivotally secured to the base 10 by a bolt 17 which extends through an opening in the base and has a 80 lock nut 18. The other end of this lever bears directly upon the contacts 15 and is provided with a suitable insulating handle 19 for moving the same back and forth over said contacts. In practice I prefer to provide the contact engaging portion of the lever 16 on opposite sides thereof with projections 20 and 21 so spaced as to serve to bring the lever 16 to a positive stop over each contact. The movement of the contact 90 lever 16 is limited by bosses 22 and 23 which are preferably formed integrally upon the base 10.

The contact lever 16 is adapted to be connected to one of the supply lines through a 95 terminal plate 24 clamped between the same and base 10. This base carries a suitable binding screw 25. The other supply wire is adapted to be connected to a terminal plate 26 secured to the base 10 by a screw 27 and 100 having a binding screw 28. For simplicity and convenience I prefer to arrange the terminal plates in close proximity and in order to avoid danger of short-circuits I prefer to provide an insulating barrier 29 between 105 these plates. This barrier preferably comprises a boss or lug formed integrally upon the base 10.

The connections between the rheostat and the motor or other translating device to be 110

controlled may be made by wires 30 and 31 connected respectively to the screw 27 of the binding plate 28 and the extreme right hand contact 15, as shown in Fig. 2. With such connections, assuming that the contact lever 16 is connected to the positive supply line, current will flow through said lever 16 to one of the contacts 15, thence through all or a portion of the resistance 12 to the extreme right hand contact 15 of Fig. 2, thence by conductor 31 through the motor or other translating device, by conductor 30 to screw 27, to terminal plate 26 and thence to the negative supply line.

5. In practice, the resistance may be insulated in any desired manner. I prefer, however, to embed the same in cement or other plastic composition 30 which may be readily applied and used to substantially fill the recess or channel 11 in which the resistance is placed.

What I claim as new and desire to secure by Letters Patent, is:

1. A rheostat comprising a flat and substantially circular base having a transverse portion of reduced cross section providing a channel around the same, a resistance wound around said base in said channel, a series of contacts mounted on said base on one side of said channel and terminals and a pivoted contact lever mounted on said base on the opposite side of said channel, said contact lever coöperating with the aforesaid contacts.

2. A rheostat comprising a substantially circular base having oppositely disposed segmental portions and an intermediate portion of reduced cross section providing a channel between said segmental portions, a resistance wound around said base in said channel, an insulating filler for said channel covering said resistance, terminals and a pivoted lever mounted upon one of said segmental portions of said base and a series of contacts mounted on the other segmental portion of said base to be engaged by said contact lever.

3. A rheostat comprising a flat base, a resistance wound around the same transversely thereof, said base having a series of aper-

tures therethrough contiguous to its edge, taps for said resistance looped through said apertures and around the edge of said base to engage certain turns of said resistance and contacts fixed to said base and connected to said taps.

4. A rheostat comprising a substantially circular and flat base, a resistance wound around said base transversely thereof leaving only segmental exposed portions of said base, one of said segmental portions of said base being provided with a perpendicularly disposed barrier, and terminals fixed to said base on opposite sides of said barrier, a lever fulcrumed to one of said terminals, and a series of contacts fixed to the other segmental portion of said base to be engaged by said lever and having electrical connection with said resistance.

5. A rheostat having a base, a resistance, contacts fixed to said base and connected to said resistance, a pivoted resilient contact arm coöperating with said contacts, said arm being yieldable perpendicularly to its plane of pivoted movement and having spaced projections extending perpendicularly to its plane of pivoted movement for centering of said arm on said contacts.

6. A rheostat provided with a base having segmental end portions and an intermediate portion of reduced cross section, a resistance wound around said reduced portion of said base, an insulating covering for said resistance, a series of contacts fixed to one segmental portion of said base and electrically connected with said resistance, a terminal plate secured to the other segmental portion of said base, a contact lever coöperating with said contacts and fulcrumed to said base to bear upon said terminal plate, a second terminal fixed to said base adjacent said terminal plate, and an insulating barrier on said base between said terminals.

In witness whereof, I have hereunto subscribed my name in the presence of two witnesses.

ALBERT J. HORTON.
